UNITED STATES PATENT OFFICE.

WILLIAM H. HALLER, OF CUMBERLAND, MARYLAND, ASSIGNOR OF ONE-THIRD TO
PERRY A. NICKLIN, OF CUMBERLAND, MARYLAND.

PIPE-COUPING.

1,135,893.

Specification of Letters Patent. Patented Apr. 13, 1915.

Application filed December 31, 1913. Serial No. 809,694.

To all whom it may concern:

Be it known that I, WILLIAM H. HALLER, a citizen of the United States, residing at Cumberland, in the county of Allegany and State of Maryland, have invented new and useful Improvements in Pipe-Couplings, of which the following is a specification.

This invention relates to pipe couplings and more particularly to air or steam pipe 10 couplings for passenger or other trains.

The principal object of the invention is the provision of simple and efficient means for coupling the train pipes of adjoining cars automatically when they are coupled 15 together so as to obviate the necessity of entering between the cars to join the hose, as is customary.

Another object of the invention is the provision of a device of this character embodying means which provides for the relative differences in the position of the adjoining cars both as to vertical and lateral displacement.

Still another object of the invention is 25 the provision of a device of this character which is arranged to automatically connect train pipes of adjoining cars and which device may be so positioned as to cut off the air or steam when the cars are uncoupled.

30 Further objects of the invention will appear as the following description is read in connection with the accompanying drawing, which forms a part of this application, and in which:—

35 Figure 1 is a detail side elevation of a pair of coupled cars showing the position of the devices thereon. Fig. 2 is a vertical sectional view taken on the line 2—2 of Fig. 1 looking in the direction of the arrow.

40 Fig. 3 is a horizontal section taken on the line 3—3 of Fig. 1. Fig. 4 is a sectional view taken on the line 4—4 of Fig. 3 and looking in the direction of the arrow. Figs. 5 and 6 are sections taken on the line 5—5 45 of Fig. 4 and showing the valve in open and closed positions, respectively. Fig. 7 is a perspective view of a locking washer. Fig. 8 is a horizontal section taken on the line 8—8 of Fig. 2.

50 Referring more particularly to the drawings, 1 and 2 represent the separate cars to be connected which are coupled as usual by the ordinary draw heads 3. Suspended from the platform or floor of the car, as is usual, 55 is the train pipe 4 which may conduct either

steam or air or any other suitable controlling medium, as is well understood.

In applying this device to the air pipe the end of the said pipe is preferably closed by a cap 5 and adjacent the cap and interposed in the length of the pipe is a valve casing 6 having one leg 7 of an angular valve body 8 seated therein. The opposite leg 9 of the valve body is seated in a casing 10 to be hereinafter described. The leg 7 is provided with oppositely extending ports 10' and 11 which form a communication between the main portion of the pipe 4 and the extension having the cap 5 so that if the apparatus should get out of order an angle cock could be applied to the extension having the cap 5 and the usual coupling hose connected thereto. Both ports 10' and 11 communicate with a horizontal port 12 formed in the leg 7, which horizontal port communicates directly with a vertical port 13 formed in the leg 9. The port or channel 13 communicates with an outlet port 14 and as the casing 10 is revolvably mounted upon the leg 9 the port will communicate with either end 15 or 16 thereof.

Secured to the end 15 is a nozzle 17 arranged to fit in the horn 18 of the coupling device of the adjoining car, this horn 18 being secured to the end 16 of the valve casing 10. The horn consists of an elongated sleeve 19 having a flared mouth piece 20 secured thereto so as to direct the nozzle into the horn and this mouth piece is so arranged as to compress a suitable packing 21 in the sleeve 19 to hold a swab 22 in place. The swab 22 is arranged to clear the nozzle 17 of any dirt or other foreign material and the packing is arranged to fit the nozzle so as to make a fluid tight joint.

It will be seen from an inspection of the drawings that when the casing 10 is arranged in position as shown in Fig. 5 that the port 14 will be open to the horn 18 and that when the casing is reversed upon the leg 9 that the port 14 will be open to the nozzle 17, while an inspection of Fig. 6 will show that when the casing 10 is turned at right angles to the line of direction of the train pipe that the air will be cut off from both the horn and the nozzle 17.

In order to support the device in proper position beneath the car body the train pipe is held in brackets 23 and the body 8 has

threaded thereinto an extension arm 24 whose terminal end is supported in a hanger 25 depending from the underneath side of the platform or floor of the car.

5 So far as described, the casing will be free to rotate upon the legs 7 and 9 and in order to prevent such action each leg is provided with an extension 26 having a flatted side 27 and fitted upon the extension is a 10 washer 28 having an aperture 29 corresponding with the shape of the extension so as to prevent its rotation thereon. The washer is provided with a plurality of raised bosses 30 extending radially and arranged 15 at quartering intervals so as to engage similarly positioned recesses or notches 31 arranged in the outer ends of the casings. These washers are held in engagement with the ends of the casing by means of springs 20 32 which surround the extensions and are arranged between the washers and suitable nuts 33 screwed upon the extension. The nuts are held in position against accidental loss by the cotter pins 34 and serve to adjust the tension of the springs 32 when necessary.

In the operation of the device the horn 18 of one car is arranged to project toward the adjoining car while the adjoining car 30 has the nozzle thereof projecting toward the horn so that when the cars are brought together to be coupled the nozzle will project into the horn, pass through the swab and packing and be free to work back and forth. 35 As the casings 10 are arranged to rotate upon the legs 9 it will be seen that any difference in relative lateral movement between the cars will not affect the connection and as

the legs 7 are rotatably mounted within the casings 6 any relative distance in position 40 vertically will not affect the connection.

It will, of course, be understood that while the casing 10 is normally held against movement through the medium of the washer 28 and the leg 7 held against movement through 45 the engagement of the washer of the casing 6 that these parts may be moved when sufficient pressure is used toward this end.

As electrical connections may be made in a similar manner I do not wish to be restricted to the showing in the present drawings but to the invention as covered by the appended claim.

What is claimed is:—

In combination, conductor elements arranged to be secured to the cars to be connected and adapted to carry a source of energy, angular controlling members having one leg pivoted in the conductor elements, coupler elements pivoted for horizontal movement upon the other leg of said angular controlling members, and means for holding the controlling members and the coupling elements in operative coupling position, said means arranged to permit relative lateral and vertical movement between the cars and to hold the coupling elements in inactive position when necessary thereby cutting off the source of energy to the coupling elements.

In testimony whereof I affix my signature in presence of two witnesses.

WILLIAM H. HALLER.
